UNITED STATES PATENT OFFICE

DENA B. COMBS, OF WAVERLY, OHIO.

SPARK-PLUG AND AIR-COMPRESSOR

1,091,295.

Specification of Letters Patent. Patented Mar. 24, 1914.

Application filed June 20, 1912. Serial No. 704,603.

To all whom it may concern:

Be it known that I, DENA B. COMBS, citizen of the United States, residing at Waverly, in the county of Pike and State of Ohio, have invented certain new and useful Improvements in Spark-Plugs and Air-Compressors, of which the following is a specification, reference being had therein to the accompanying drawing.

10 This invention relates to a combined spark plug and pump connection which is used in connection with one of the cylinders of an internal combustion engine.

The principal object of the invention is 15 to provide a device which will act as a spark plug of an engine but which may be converted into a device by means of which one of the cylinders may be converted into a pump for inflating tires of automobiles.

20 This is accomplished by providing an improved spark plug with a valve construction which may be turned on or off so that when the piston head moves away from the spark plug, the suction will be through the spark plug instead of through the intake from the carburetor thereby preventing the gas from the carburetor from entering the cylinder when it is desired to use the cylinder as a pump.

25 30 This invention is illustrated in the accompanying drawings, wherein:—

Figure 1 is a view showing a fragmentary view of two cylinders and a sectional view of the intermediate cylinder, the improved 35 spark plug being connected with the intermediate cylinder. Fig. 2 is a vertical sectional view through the spark plug. Fig. 3 is a section along the line 3—3 in Fig. 2. Fig. 4 is a section along the line 4—4 in Fig. 2.

40 Referring to the accompanying drawings, it will be seen that this invention is connected with the cylinder 10 which is located between the cylinders 11 and 12. It is, of course, understood that it is immaterial 45 which of the cylinders this spark plug is connected with, it being understood that the spark plug is connected with one of the cylinders, the remaining cylinders being provided with the ordinary spark plugs. This 50 is necessary since when this device is in use, the cylinder with which the improved spark plug is connected forms a pump and it is necessary to have the remaining cylinders provided with the ordinary type of

spark plug so they may rotate the driving 55 shaft of the engine so that the driving shaft will reciprocate the piston, thereby causing the cylinder having the improved spark plug to act as a pump. This improved spark plug comprises the base portion 13 60 having the depending threaded extension 14 which is provided with the central opening 15. Openings 16 lead from the opening 15 and communicate with the sloping upper face 17 of the base 13. A neck 18 is carried 65 by the base 13 and is provided with an upper end portion 19 which is internally and externally threaded as is clearly shown in Fig. 2. This neck and central portion of the base 13 are provided with an opening 70 20 provided with an enlarged outer end portion to form the shoulder 21. This opening 20 extends through the base to a point adjacent the inner ends of the openings 16, the opening 20 communicating with these 75 openings 16. A collar 22, which forms a valve for this spark plug, is mounted upon the sloping face of the base and is provided with a concaved lower face so that it fits tightly upon this flat face 17, thus forming 80 a tight joint. The collar is provided with a continuous annular pocket 23 formed in its lower portion which is positioned in the path of the openings 16 so that the air which is driven out of the cylinder may 85 enter the pocket and pass out of the pocket through the discharge cock 24. Small pockets 25 lead from the annular pocket 23 and are provided with reduced outlets 26, screens 27 being positioned in the inner 90 ends of the pockets 25. Balls 28 are positioned in the pockets 25, the screens preventing the balls from dropping into the pocket 23 but permitting air from the cylinder to pass through the screens so that 95 when the air is driven out of the cylinder by the piston, the balls 28 will be forced into the inner ends of the openings 25 thereby preventing air from escaping through the openings and forcing the air to pass 100 out through the cock 24. A rubber tube 29 is connected with this cock 24 when desired, so that air may be conveyed to the tires of the automobile thus inflating the tires. Locking nuts 30 are screwed upon the upper end 105 portion 19 of the neck 18 so that the collar 22 will be held tightly in place. These nuts may be adjusted so that while the collar

fits tight enough to prevent leakage, it may be turned a sufficient amount to bring the openings 26 out of alignment with the openings 31 formed in the nuts 29 and 30. An arm 32 extends from the collar, and the lever 32' is pivotally connected with the arm so that the turning of the arm will be greatly facilitated.

An insulating stick 33 is placed in the opening 20 and is provided with an enlarged shoulder 33' which rests upon the shoulder 21. A collar 34 is threaded into the upper portion 19 of the neck 18 and fits against the upper face of the shoulder 33' so that the insulating member is tightly held in place. A threaded stem 35 passes through the insulating stick and is threaded through the central portion 36 of the base 13. This stem 35 forms one pole of the spark plug, the second pole 37 being carried by the neck 14. An arm 38 is mounted upon the stem 35 and has its free end resting upon the valve 39 of the cock 24 so that a short circuit will be formed through the spark plug when pumping. Clamping nuts 40 are screwed upon one end of the stem 35 so that this arm 38 may be held in place.

When the engine is in operation, the collar 22 is turned so that the openings 26 are out of alignment with the openings 31, and the valve 39 is turned so that all communication is cut off with the outer air. The device will then operate as an ordinary spark plug and explodes the gas in the cylinder so that the cylinder assists the remaining cylinders to rotate the crank shaft. When it is desired to inflate a tire, the collar is turned to the position shown in Figs. 1 and 2, and the valve 39 of the cock 24 turns so that a clear passage is formed through the cock. The tube 29 is connected with the cock and with the valve of the tire, and the engine is then started. The cylinders 11 and 12 rotate the crank shaft and the crank shaft reciprocates the piston of the cylinder 10 so that the piston upon a downward stroke causes a suction through the openings 31, 16, and 15, into the cylinder. Upon the return stroke the air passes through the openings 15 and 16 into the pocket 23 and out through the cock 24 into the tube 29 through which it passes into the tire. It is, of course, obvious that when the piston is upon the downward stroke that it takes less effort to suck air through the spark plug than to suck gas through the valve controlling the carburetor and, therefore, the suction will be through the spark plug and not through the carburetor. Therefore, the gas from the carburetor does not enter the cylinder and it is, therefore, obvious that no gas will be forced into the tire. It is also obvious that when air is forced into the spark plug by the piston, that the force

of air drives the ball valves 28 into the openings 26 thus closing the openings and causing the remaining portion of air to pass into the tube 29 and from thence into the tire. After the tire has been pumped up the collar is turned to bring the openings 26 out of alignment with the openings 31, and the valve 39 turned to a closed position and the suction will then be through the carburetor, and the spark plug act as an ordinary spark plug to explode these gases.

Having thus described the invention, what is claimed as new is:—

1. A spark plug comprising a base provided with a plurality of openings formed therethrough, a pole extending through said base, a collar mounted upon said base and provided with an annular pocket in its lower portion registering with the openings of said base and with an outlet leading from the side of said pocket, valve pockets formed in the upper portion of said collar and leading from said first mentioned pocket, controlling valves mounted in said valve pockets, and means carried by said base for rotatably connecting said collar with said base.

2. In a spark plug a base having openings formed therethrough, a collar rotatably mounted upon said base and provided with a pocket communicating with the openings formed in said base and with valve pockets extending above said first mentioned pocket, valves mounted in said valve pockets, and securing nuts mounted upon the upper portion of said base to hold said collar upon said base and provided with aligned openings registering with the openings of said valve pockets when said collar is rotated to bring the openings of the valve pockets into registry with the openings in the securing nuts.

3. A spark plug of the character described comprising a body portion provided with a vertically extending opening and with openings leading from its upper face and communicating with the vertically extending opening, a pole insulated in the vertically extending opening, a chambered controlling collar adjustably mounted upon said body portion and provided with inlet openings leading from its chamber, valves carried in the openings of said collar, an outlet cock leading from the chamber of said collar, perforated clamping nuts mounted upon said body portion to hold said collar upon said body portion, the turning of said collar bringing its openings into and out of registry with the openings of said nuts, and an arm leading from said pole to said outlet cock.

4. A spark plug comprising a perforated base having a contact pole, an insulated pole passing through said base and terminating adjacent the pole of said base, a rotatable

collar carried by said base and provided with a chamber inclosing the openings of said base and provided with inlet openings, valves in the inlet openings of said collar, 5 an outlet cock leading from the chamber of said collar, a securing nut holding said collar upon said base and provided with openings registering with the inlet openings of

said collar, and an arm leading from said insulated pole to said cock.

In testimony whereof I hereunto affix my signature in presence of two witnesses.

DENA B. COMBS.
